UNITED STATES PATENT OFFICE.

GIUSEPPE ORESTE TIBERTI, OF GENOA, ITALY.

ROTARY GAS-ENGINE.

1,309,554.

Specification of Letters Patent.

Patented July 8, 1919.

Application filed April 26, 1917. Serial No. 164,708.

To all whom it may concern:

Be it known that I, GIUSEPPE ORESTE TIBERTI, subject of the King of Italy, residing at Genoa, Italy, have invented certain new and useful Improvements in Rotary Gas-Engines, of which the following is a specification.

This invention relates to improvements in rotary internal combustion engines of the type in which the charge is drawn and compressed into a stationary compartment and afterward delivered into a second compartment, where it is exploded and discharged.

According to the invention two rotors are concentrically mounted within two compartments of elliptical shape and each rotor is provided with an even number of pistons which move radially in said compartments. Two opposite pistons in one compartment simultaneously draw charges into that compartment while two other pistons in the same compartment act to compress the charges previously introduced. The compressed charges are forced into the second compartment and there two opposite pistons, of that compartment, are contemporaneously subjected to explosions.

One of the principal objects of the invention is to provide a device of this character, which will entirely eliminate the necessity of employing valves, as the function of valves will be assumed by the pistons.

A further object of the invention is to provide the free end of each piston with special means which will at all times tightly engage the elliptical walls of the compartments without permitting leakage of the explosive mixture or gases past the same.

With the foregoing objects outlined and with other objects in view, my invention consists in the novel features hereinafter described in detail, illustrated in the accompanying drawings, and more particularly pointed out in the appended claims.

Referring to the drawing:

Figure 1 is a vertical sectional view of my improved engine taken on the line 1—1 of Fig. 2.

Fig. 2 is a sectional view taken on the line 2—2 of Fig. 1.

Fig. 3 is a plan view of the engine casing, with certain of the interior parts shown diametrically in dotted lines.

Fig. 4 is a diagrammatic view showing the cycle of the motor.

In the drawings A designates the engine casing which is of cylindrical shape and is provided on its interior with two chambers 1 and 2, arranged parallel to each other. The chamber 2 has parallel side walls 3 and 4 and the chamber 1 has similar walls 4 and 5. The chamber 2 has an elliptical wall 7 and the chamber 1 has a similar wall 6.

It will be noted from Fig. 1, that the elliptical chambers 1 and 2 are arranged in crossed position and that the longest diameter of the chamber 1 is at right angles to the longest diameter of chamber 2.

Mounted centrally in the casing A is a shaft 11 to which is fixed a rotor 12 formed of two circular disks 13 and 14. These disks are located in the chambers 1 and 2 and their sides are arranged parallel to the walls 3, 4 and 5.

Packings 8, 9 and 10 are arranged between the shaft 11 and the casing to prevent leakage.

Each one of the disks 13 and 14 carry an even number of radially movable pistons 15^a, 15^b, 15^c, 15^d, 15^e, 15^f, 15^g, and 15^h, having movable heads 16, which are held in contact with the elliptical walls of the chambers as the disks rotate, by means of coil springs 17. The heads 16 have their outer surfaces machined and shaped between the minimum and maximum curvatures of the elliptical walls 6 and 7, so as to have a maximum bearing on these walls at all times during the rotation of the rotor. This shape can be clearly seen from Fig. 1.

There are four pistons carried by each of the disks and these pistons are equally spaced on the circumferences of the disks.

18 represents openings, communicating with tubes 19, by which the mixture of gas coming from the carburetor enters the chamber 1 at diametrically opposite points closely adjacent the shortest diameter of the chamber. Outlet openings 21 for the compressed mixture are arranged diametrically opposite each other and closely adjacent the longest diameter of the chamber 1. Passages 20 lead from the openings 21 to openings 22, arranged diametrically opposite to each other in the elliptical wall 7 of the chamber 2, and these openings are located substantially midway between the longest and shortest diameters of the elliptical wall 110 as shown in Fig. 1. Exhaust ports 23 for the chamber 2 pass through the wall 7 near

its longest diameter and these ports are also arranged diametrically opposite each other.

The casing A is hollow, as shown at 24, for the purpose of water cooling the same, and the periphery of each disk 13-14 is provided with a series of circumferentially extending grooves 25, which permit explosive mixture to pass from the space formed between the periphery of a disk and the wall 10 of a compartment to the opposite space between that disk and the wall of said compartment.

The operation is as follows:

Assuming that the parts are in the position shown in Fig. 1 and that two of the 15 pistons 15^a and 15^b in the chamber 1 are in the position indicated by I-I in Fig. 4, that is, standing closely adjacent the admission openings 18, then if the shaft 11 is 20 turned to move the rotor in the direction of the arrows shown in Figs. 1 and 4, these pistons in moving toward the openings 21, will simultaneously draw the explosive mixture into chamber 1 at two opposite points. 25 This will continue until the last mentioned pistons reach the position II-II in Fig. 4, then as they move past the ports 21, the mixture drawn in to chamber 1 will be compressed and forced through the openings 21, 30 by the following pistons 15^c and 15^d, which in moving away from the openings 18 will draw mixture in on one side of the pistons and be compressing the mixture, previously drawn in, on the other side of the pistons. 35 In other words, after the rotor is in operation, two opposite pistons in rotating, will be drawing explosive mixture into the chamber 1 by the suction created in the movement of the pistons away from the openings 18, and they will also be compressing the previously drawn in mixture by moving toward the openings 21.

The compressed mixture is thus forced through the passages 20 to the openings 22 45 in the chamber 2 and between pairs of successive pistons of that chamber. When the pistons 15^c and 15^d in the chamber 2 cover the openings 22, the explosion of the mixture between these pistons and the pistons 15^a and 15^b takes place in the parts of the chamber 2 marked 30, by means of suitable spark 50 plugs (not shown). The pistons 15^c and 15^d receiving the force of the explosions, at the time of explosion, are in the position indicated by line III-III in Fig. 4. The chambers of explosion are formed in part by the curved surface of the disk 14; in part by the elliptical surface of the chamber 2; the walls 4 and 5 of the casing; and by the 55 surfaces of adjacent pistons. When the mixture is exploded, it will drive the rotor in the direction indicated by the arrows and the spent gases will be exhausted through the ports 23 (position IV-IV of Fig. 4.)

60 The four pistons of the chamber 2 being

equally spaced around the periphery of the disk 14, are arranged out of alignment with the pistons of the chamber 1, so that when the double explosion takes place, in the chamber 2, against two opposite pistons, the 70 other six pistons are closing the ports 18, 21 and 22. During operation, after two opposite pistons in chamber 1 have passed the 75 openings 21, the gases trapped between these pistons and the preceding ones of the chamber 1, will be permitted to pass through the grooves 25 from one of the crescent shaped spaces to the other and in consequence the trapped gases will be mixed with the incoming gases.

It will be seen from Fig. 1 that after the 80 pistons 15^a and 15^b have passed the openings 22, the gas being forced into the chamber 2 will be led into spaces 2^a which are open to the atmosphere through the exhaust ports 85 23, but as the pistons 15^c and 15^d move away from the ports 22, they will draw the explosive mixture with them and thus prevent the mixture from escaping through the ports 23.

From the foregoing it will be seen that a 90 motor constructed as set forth will produce eight explosions during a single rotation of the shaft, and the results will be similar to the ordinary four cycle engine having eight 95 cylinders.

What I claim and desire to secure by Letters Patent is:

1. A rotary internal combustion engine comprising a casing provided with a plurality of chambers having parallel side walls 100 and elliptical circumferential walls, which are arranged in crossed relation relative to one another, the elliptical wall of one chamber being provided with diametrically opposite openings for the admission of the 105 explosive mixture and with diametrically opposite openings for the discharge of the compressed mixture from said chamber, passages connecting the discharge openings of the first chamber in communication with 110 inlet openings diametrically oppositely arranged in the elliptical wall of the second chamber, rotatable disks mounted in said chambers and each carrying an even number of pistons, and springs for forcing said 115 pistons toward said elliptical walls, the pistons of the two disks being arranged out of alignment.

2. A rotary internal combustion engine comprising a casing provided with a plurality of parallel arranged chambers having parallel side walls and elliptical circumferential walls, the circumferential wall of one chamber being arranged in crossed relation relative to the circumferential wall of the 125 other chamber, diametrically opposite inlet ports for one chamber arranged in its elliptical wall near its shortest diameter, for admitting explosive mixture to said chamber diametrically opposite outlet ports arranged 130

in the last mentioned wall near its largest diameter for permitting the discharge of said mixture from said chamber, passages placing said last mentioned openings in communication with diametrically opposite openings arranged in the elliptical wall of the other chamber at points midway between the longest and shortest diameters of the elliptical wall of the second chamber, a shaft extending through the casing, disks fixed to said shaft and located in said chambers, an even number of pistons carried by each of said disks and the pistons of each disk being

arranged out of alignment with the pistons of the other disk, means for forcing said pistons toward the elliptical walls of said chamber, and heads carried by said pistons and provided with a plurality of differently curved surfaces designed to snugly engage the elliptical walls, as the disks rotate.
